UNITED STATES PATENT OFFICE.

RAY C. NEWHOUSE, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

REVOLVING GRIZZLY.

1,135,606.

Specification of Letters Patent. Patented Apr. 13, 1915.

Application filed July 6, 1914. Serial No. 849,860.

To all whom it may concern:

Be it known that I, RAY C. NEWHOUSE, a citizen of the United States, residing at Milwaukee, in the county of Milwaukee and 5 State of Wisconsin, have invented a certain new and useful Improvement in Revolving Grizzlies, of which the following is a specification.

This invention relates to improvements 10 in the construction of grizzlies and is especially applicable to revolving grizzlies adapted for use in crushing plants wherever a rough separation of coarse and fine material is desired.

15 An object of the invention is to provide a revolving grizzly which is simple in construction and efficient in operation.

One of the more specific objects is to combine a feeding means with a grizzly of the 20 drum type, for the separation of the fine material and to permit entry of this material through the drum, the drum being formed to permit relatively free discharge of the material from its interior.

25 Another object is to provide a grizzly of maximum capacity and in which the rate of separation of the fine from the coarse material may be readily altered.

It has heretofore been proposed to construct 30 a revolving grizzly of a circular series of parallel bars rotatable about a central shaft. This device is objectionable since some of the fine material which passes through the spaces between adjacent bars 35 will not pass readily from the interior of the grizzly during exit. This undesirable result is due to the fact that a piece of material which passes through the space between parallel bars at one time may so 40 alter its position that it will not pass freely through the same space at another time, but instead will become wedged between the bars. In order to avoid this undesirable result, the adjacent bars of the grizzly forming 45 the subject of the present invention, are placed at an angle to each other, thus rendering the space between successive bars of greater width at the discharge end of the bars than at the inlet portion of the grizzly.

50 The means for feeding the material is located adjacent the portion of the grizzly where the openings between adjacent bars are narrowest, while the discharge from the grizzly extends throughout the entire length

thereof. In this manner the discharge opening from the grizzly is considerably larger than the inlet opening leading thereto, thus assuring a rapid passage of the fine material through the device. 55

While the drawing discloses a grizzly 60 drum comprising a plurality of bars converging toward a central plate or disk, it should be understood that the invention as claimed is intended to cover any grizzly in which a feeder co-operates with a drum in 65 such a manner as to permit entry of the fine material through the drum, the drum being formed to permit free exit of the material from its interior.

A clear conception of an embodiment of 70 the invention may be had by referring to the drawing accompanying and forming a part of this specification in which like reference characters designate the same or similar parts in the several views. 75

Figure 1 is a front view of a revolving grizzly showing fragments of the supporting bearings in section, and showing also fragments of the storage bin and discharge chute. Fig. 2 is a transverse vertical section through the grizzly, the section being taken on the line II-II of Fig. 1, the figure also showing a section through the storage bin, the feed chute and the discharge chute. 80

85 In the embodiment of the invention disclosed in the drawing, the grizzly comprises a plurality of longitudinal elements or bars 6 arranged to form a substantially cylindrical drum. The bars 6 are arranged in two 90 circular sets having their adjacent ends connected to the intermediate member or disk 10 and having their outer ends connected to the end members or disks 4. The disks 4, 10, are concentrically mounted upon a rotatable shaft 1 which is supported in the bearings 5. The shaft 1, disks 4, 10, and bars 6 are revoluble by means of a driving cable 3 which coacts with a suitable sheave 2 connected to one of the end members or disks 4. 95 The adjacent bars 6 are placed at an angle to each other, thus rendering the space between them of increasing width proceeding longitudinally of the bars and toward the disks 4. By this arrangement of the bars 6, 100 a grizzly having a mid portion of considerably smaller diameter than its end portion, 105 is produced.

The retainer for the unseparated material, which is disclosed as a storage bin 8, is filled with the material which contains a mixture of large pieces 11 and small pieces 12. The storage bin 8 is provided with a discharge opening which delivers the material onto a feeding chute 7. The chute 7 is directed toward the mid portion of the grizzly at an angle of approximately 45 degrees. The feed chute 7 is of considerably less width than the length of the grizzly, thus confining the feed to the narrowest portions of the spaces between the grizzly bars 6. Adjacent the lower side of the grizzly 15 and substantially in line with the feeding chute 7 is located the discharge chute 9 for conveying away the large pieces 11 of the material.

During the normal operation of the 20 grizzly, the drum is rotated in an anticlockwise direction as indicated by the arrow in Fig. 2, by means of power applied through the driving cable 3. The material to be separated is discharged from the storage bin 8 25 by gravity and slides down the feeding chute 7 against the upper bars 6 of the rotating drum. As the grizzly bars move past the lower end of the chute 7, the pieces 12 of the material which are small enough to 30 pass directly through the spaces between the adjacent bars 6, fall by gravity through these spaces and into the interior of the grizzly drum. The large pieces 11 are carried over the top of the drum by the forward movement of the bars 6 until they 35 reach a position where gravity will cause them to drop upon the discharge chute 9 which conveys them away. After the pieces 12, which in the present case constitute the 40 fines, pass through the spaces between the upper bars 6, they fall through the interior of the drum and strike the bars 6 in the lower portion thereof. If the pieces 12 of the material thus passing through the interior of the drum are small enough to pass 45 directly through the spaces between the lower bars 6 at the portions thereof which the material first strikes, the pieces pass directly through these spaces and are 50 discharged from the grizzly. Some of the pieces 12 may, however, so shift their position during their passage through the interior of the drum that instead of passing directly through the spaces between the adjacent lower bars 6, they tend to lodge between these bars. Due to the longitudinal 55 widening of the discharge spaces and of the longitudinally free formation thereof, the pieces 12 which tend to lodge between the lower bars are urged toward the ends of the grizzly drum by the action of gravity and by the impact of other pieces falling 60 against them, until they reach a point in the space between the adjacent bars through

which they can readily pass and be freely 65 discharged from the interior of the grizzly.

When the grizzly is at rest the material from the storage bin 8 builds up upon the feeding chute 7 and rests against the upper bars 6 of the drum. The rate of discharge 70 of the material from the storage bin 8 is approximately proportional to the rate of rotation of the grizzly, so that the rate of separation and of the discharge of the material from the storage bin 8 is dependent 75 upon the rate of rotation of the grizzly drum. This feature of the present invention permits utilization of the grizzly as a feeder, the rate of feeding being alterable by varying the rate of rotation of the drum. 80

By forming the grizzly with a feeding mid portion of relatively small diameter and with end portions of large diameter, and feeding the material to the portion of small diameter, the large pieces of material tend 85 to remain near the mid portion of the drum and outward movement of these pieces toward the ends of the drum is gravitationally opposed.

Although the drawing discloses a grizzly 90 drum formed of circular series of bars 6, the adjacent bars being disposed at an angle to each other to form a drum having a mid portion of reduced diameter, it should be understood that the invention includes 95 within its scope any modification of the drum whereby a feeding means for material combines with the drum to separate from the material the fines for entry therethrough, the drum being formed to permit 100 passage of material therefrom more freely for exit than during entry.

While it is deemed unnecessary to illustrate specific modifications of the form of the invention as shown, it is intended to include such modifications within the scope of this invention. It should therefore be understood that it is not desired to be limited to the exact details herein shown and described for various modifications may occur to a person skilled in the art. 110

It is claimed and desired to secure by Letters Patent,—

1. In a grizzly, a feeding means for material combined with a drum for separating 115 from the material the fines for entry through said drum, said drum being formed to permit passage of material therefrom more freely for exit than for entry thereof into said drum.

2. In a grizzly, a feeding means for material combined with a drum for separating from the material the fines for entry through said drum, said drum being formed to permit passage of material therethrough 125 more freely for exit than for entry thereof into said drum.

3. In a grizzly, a feeding means for ma-

terial combined with a drum for separating from the material the fines for entry through said drum, said drum being formed to permit passage of material therethrough more freely for exit than for entry thereof into said drum, and means for rotating said drum.

4. In a grizzly, a plurality of spaced bars arranged to form a drum, and feeding means for material combined with said drum for separating from the material the fines for entry to said drum through the spaces between said bars, said spaces being formed to permit passage of material therethrough more freely for exit than for entry thereof into said drum.

5. In a grizzly, a plurality of spaced bars arranged to form a drum, feeding means for material combined with said drum for separating from the material the fines for entry to said drum through the spaces between said bars, said spaces being formed to permit passage of material therethrough more freely for exit than for entry thereof into said drum, and means for rotating said drum.

6. In combination, a drum having a portion forming a free passage for fine material therethrough and having another portion forming a freer passage for fine material therethrough, means for feeding fine and coarse material to said first mentioned portion, said means being so disposed and said drum being formed to oppose the passage of said coarse material toward said second mentioned portion, and means for rotating said drum.

7. In combination, a drum having a portion permitting passage of only fine material therethrough and having another portion permitting freer passage of fine material therethrough, means for feeding fine and coarse material to said first mentioned portion, the feed side of said drum being gravitationally disposed to oppose the pas-

sage of material toward said second mentioned portion, and means for rotating said drum.

8. In combination, a plurality of spaced bars arranged to form a drum, the spaces between adjacent bars increasing in width proceeding longitudinally of said drum, means for feeding material only to the outside of said drum at the narrowest portion of said spaces, means for conveying away one of the separated portions of said material, and means for rotating said drum.

9. In combination, a drum having a peripheral opening thereto increasing in width proceeding longitudinally of said drum, means for feeding material only to the outside of said drum at the narrowest portion of said opening, means for conveying away one of the separated portions of said material, and means for rotating said drum.

10. In combination, a revoluble series of elements having longitudinally free spaces between them, adjacent elements of said series being arranged at an angle to each other to render the spaces therebetween of increasing width proceeding longitudinally of said elements, means for feeding material to the narrowest portions of said spaces, and means for revolving said elements.

11. In combination, a plurality of spaced end members revoluble about an axis, a plurality of spaced bars connecting said members, the spaces between said bars being of greatest width adjacent said end members, means for feeding material to said spaces, and means for revolving said members and said bars.

In testimony whereof, the signature of the inventor is affixed hereto in the presence of two witnesses.
